UNITED STATES PATENT OFFICE

161,749

CORSAGE UTILITY STAND

Robert L. Griner, Kansas City, Mo.

Application March 3, 1950, Serial No. 8,318

Term of patent 7 years

(Cl. D35—3)

To all whom it may concern:

Be it known that I, Robert L. Griner, a citizen of the United States, residing at Kansas City, in the county of Jackson and State of Missouri, have invented a new, original, and ornamental Design for Corsage Utility Stand, of which the following is a specification, reference being had to the accompanying drawing, forming a part hereof.

Figure 1 is a side view of a corsage utility stand, showing my new design.

Figure 2 is a rear elevational view; and

Figure 3 is a front perspective view on an enlarged scale.

I claim:

The ornamental design for a corsage utility stand, as shown.

ROBERT L. GRINER.
